INCORPORATED, OF NEW YORK, N. Y., A CORPORATION OF MASSACHUSETTS

KNITTING MACHINE

Application filed February 17, 1923. Serial No. 619,800.

This invention relates generally to knitting machines, and more specifically to adjunctive mechanism of a type useful in effecting transfer of the product of such machines to the points of quill bars or quill rings as the case may be, so that the fabric may, in turn, be transferred to other machinery for the performance of further work upon it.

Although my invention, in its broader aspects, is capable of universal application to knitting machines, special advantages are derived by its use with rotary stocking knitters, and I have therefore herein shown and described the same in connection with such a machine.

The main object of the present invention is to enable all the operations necessary or essential to the transfer of a knitted fabric from the needles of the producing machine, to be effected substantially automatically, and to provide mechanism whereby these ends are accomplished both rapidly and with precision, to the absolute avoidance of stitch dropping, and without requiring any special skill on the part of the operative attending the machine.

A further object of my invention is to secure the aforesaid desiderata in a transfer means capable of being applied to standard forms of knitting machines without requiring any changes whatever in their inherent mode of action nor in the essential parts constituting the same.

Other objects and attendant advantages will become readily apparent from the detailed description which follows of a typical embodiment of my invention.

In the drawings Fig. I is a side elevation of a portion of an ordinary automatic, circular stocking knitting machine conveniently showing my invention.

Fig. II is an end elevation of the same as viewed from the left of Fig. I.

Fig. III is a similar illustration, viewed

from the right of Fig. I, showing more particularly the details of the auxiliary drive for the needle cylinder comprehended by my invention and which functions after the knitting has been completed for the purpose of effecting transfer of the fabric.

Fig. IV is a top plan view, on a larger scale than the preceding figures, of the annular web holder head which carries the cams for operating said web holders.

Figs. V and VI are views similar to Fig. IV with certain parts of the web holder actuating mechanism shifted to other positions from those shown in the latter figure.

Fig. VII is an enlarged vertical sectional view through a portion of the needle cylinder illustrating the operation of certain special cams which prepare the needles for reception of the transfer ring, also showing the manner in which the latter is placed on the needles.

Fig. VIII is a fragmentary sectional view showing a common form of means whereby the knitting cams are retracted relative to the needles to permit needle leveling.

Fig. IX is a perspective view of one of the special elements associated with the pawling mechanism for the pattern drum of the machine.

Fig. X is a side view of the element aforesaid showing the relation of the pawls thereto.

Fig. XI is a detail illustration, more or less diagrammatically represented, showing the manner in which the loops or stitches of the terminal course of the knitted web are enlarged through abnormal projection of the web holders, to facilitate reception of the quills or points of the transfer ring.

Figs. XII and XIII are fragmentary elevational views illustrating, in different positions, certain details of the mechanism for actuating the yarn feed preparatory to transfer.

Figs. XIV and XV are further illustra-

tions showing this mechanism in section; and,

Fig. XVI is a detail illustration showing the end or nose of the yarn feed in plan and 5 the normal relation of the same to the needles of the machine.

Referring first more particularly to Figs. I, II, and III of the drawings, it will be observed that the familiar parts of the knitting machine there shown include a needle cylinder 1 which is suitably mounted for rotation on a bed plate 2 supported by a frame comprehensively indicated by the numeral 3. Attached adjacent the top of the 10 needle cylinder 1 is the usual head 4 for the web holders which cooperate with the needles in a well known manner during stitch formation. The needle cam shell or ring represented at 5 comprises a section or 15 block 6 which carries the main knitting cams 7, see Fig. VIII, and is retractible radially of the cylinder 1 for needle leveling, by virtue of being slidably mounted on the bed plate 2. This block 6 is provided with a lateral 20 projection 8 slotted longitudinally for passage of a thrust bar 9 having a cam protuberance 10 which is designed to engage a roller pin 11 spanning the slot to withdraw the block 6 in opposition to a compression 25 spring 12. This spring 12 tends to maintain the block 6 in its normal forward or active position, one of its ends resting within a recess formed in a post 13 whereto the thread feed ring 14 is pivoted, said post being 30 im- 35 movably secured to the bed plate 2 of the machine. The thrust bar 9 is suitably guided for longitudinal shifting, induced at proper times, by ridges or lugs 16^a Fig. VIII on a cam drum 16, said cam drum operating in an 40 auxiliary capacity to the main or pattern drum shown at 17, and ordinarily controlling among other instrumentalities associated with the machine, the interchangeable 45 thread feeds which for brevity of illustration have been omitted from the drawings. The auxiliary cam drum 16 is rotated from the main cam drum 17 through the medium of an interposed gear train including spur wheels 18 and 19, see Fig. III. Associated 50 with the main cam drum 17 is a ratchet wheel 20 which, during the normal operation of the machine, is picked by a pawl 21. This pawl 21 is reciprocated by a double armed oscillating element 22 free on the shaft 23 upon 55 which the auxiliary cam drum 16 is mounted, and is actuated by virtue of being coordinated through a link 24, with a crank 25 on a counter-shaft 26 suitably journaled in the frame 3. The shaft 26 receives motion 60 from the main drive shaft 27 of the machine through gearing 28. In addition to the usual tight pulley (not shown) the shaft 27 carries a loose pulley 29 to which I relegate special 65 functions which will hereinafter be described.

The foregoing is of an introductory nature and will serve to distinguish between those parts which are standard or common in ordinary knitting machines from the mechanism comprehended by, and novel to my invention as set forth in the descriptive matter which follows.

The cam ring 5 is slotted for the reception and guidance of a cam 30, which, when raised to the position shown in dotted lines in Fig. I, acts upon the butts of all the needles to elevate them to the latch clearing point, so that the stitches will be cast when the needles are subsequently drawn down during transfer. Fixedly mounted to the ring 5 directly adjacent the guide slot for the cam 30, is a cam 31 adapted to slightly depress some, preferably half the needles which have been raised by the cam 30 to produce a line of demarcation which enables, 70 through the guidance thus afforded, the proper application to the needles of a transfer device in the form of a ring such as shown and described in my Patent No. 1,348,195 of August 3, 1920, so that one-half of the quills of said ring will engage the stitches around the mouth of the toe pocket of the stocking of the web produced by the machine, and the other half, the remaining stitches. This transfer ring, partly represented at 32 in Fig. VII of the drawings, is so constructed as will be noted from the patent, that those points or quills which engage the first series of stitches can be folded over to register with the others, thus permitting the doubled loops to be subsequently joined by sewing in a machine such as shown and described in my Patent No. 1,239,241 of September 4, 1917, in order to close the toe pocket of the stocking. This reasoning applies of course to the closing of the open mouth of any tube produced by the machine. A convenient way of dividing the needles into two groups is to position the depressing cam 31 so as to act only upon those needles with long butts such as ordinarily extend half way about the cylinder in standard automatic seamless hosiery machines. The sorting action of the cam 31 is shown diagrammatically in Fig. I, and again in Fig. VII where the long butt needles are indicated at "N" and the short butts at "n." Shifting of the cam 30 is controlled by a cam lug 33 on the inner periphery of the auxiliary cam drum 16, said cam acting upon a roller at the lower end of a rod 34 pivotally hung from one extremity of a lever 35 connected to the cam 30, said lever being mounted to swing about a fixed fulcrum 36 intermediate its ends. A spring 37 (Fig. I) effective upon the rod 34, serves to maintain the roller 38 on the lower end of the latter, at all times in operative contact with the inner periphery of the auxiliary cam drum 16.

In the head 4 at the upper end of the

needle cylinder 1 are radially guided the web holders indicated at 40, in Fig. VI. In addition to acting in their usual capacity of engaging the sinker wales of the terminal course of stitches upon the needles to prevent them from being raised during the elevation of the needles, I employ the web holders 40 as sinkers in a manner which will be presently explained. The web holders 40 have the usual upwardly projecting butts 39 (Fig. VII) adapted to engage within a raceway in a cam ring 41 of the head 4 mounted for independent shifting upon the web holder supporting and guiding dial in the customary manner. The raceway in the cam ring 41 is intercepted in the present instance by two web holder projecting cams 42 and 43, and a web holder retracting cam 44, as shown in detail in Figs. IV, V and VI. Projecting cams 42 and 43 are radially guided in suitable slots in the cam ring 41 so as to be free for movement inwardly and outwardly therein to operative or inoperative positions, the cam 43 being also susceptible of independent movement through the medium of an upwardly projecting pin 45 adapted to an inclined slot 46 in a swinging plate 47, said plate being pivoted at 48 and having its swinging movement restricted by a pin 49 projecting up through a slot 50 therein. Normally, the swinging plate 47 is retained in the position shown in Fig. IV by means of a leaf spring 51 which acts upon a pin 52 depending from said plate, but by means hereinafter described, the swinging plate 47 can be shifted from the position shown in Fig. IV to that shown in Fig. VI in order to affect abnormal inward projection of the web holders 40 relative to the needles when desired. As a means for shifting the projecting cams 42 and 43 simultaneously from the position shown in Fig. IV to that in Fig. V, I provide a segmental slide 53 with an inclined or tangential slot 56 operative upon an upstanding pin 57 on the projecting cam 42 in the manner similar to that described in connection with the slot 46 and pin 45 for the projecting cam 43. Pins 54, 54^a projecting through arcuate slots 55 in the segmental slide 53 serve to guide the latter for circumferential shifting on the ring 41. The segmental slide 53 is maintained normally against movement in the position shown in Fig. IV by means of a freely pivoted gravity catch 60, such catch being notched to engage one end of said slide as clearly shown in Fig. I. When it is desired to release the segmental slide 53 for shifting, this is effected by means of a spring tongue 61 depending at an inclination from a link 62. One end of this link 62 is slotted for guidance by the pin 54^a aforementioned, while its opposite extremity is pivotally connected to one arm of a bell crank lever 63 ful-

crumed for free movement to a fixed bracket 64 extending upwardly from the bed plate 2. From the other arm of the bell crank lever 63 is pivotally suspended a vertical thrust rod 65 with a roller 66 adapted to be engaged by a cam lug 67 on the auxiliary cam drum 16 see Figs. I and II. Disposed adjacent the link 62 is a companion link 68 having one end slotted at 59 for guidance by the pin 54^a and its opposite extremity connected to a bell crank 69 pivoted, with the bell crank lever 63, to the fixed bracket 64. The bell crank lever 69 has in turn pivotally suspended from its other arm a thrust rod 70 adapted to be actuated by cam lugs 71 and 72 lying in a plane adjacent to the cam lug 67 on the drum 16. The link 68 carries a depending pin 73, which, during the inward thrust of said link, engages the projecting extension 74 of the swinging plate 47 to overcome the action of the leaf spring 51 and thrust the cam 43 inward, the segmental slide 53 being at this time locked against movement by the catch 60. When, however, the catch 60 is released, additional movement transmitted to the link 68 by virtue of the greater depth of the cam lug 72 on the drum 16, will cause the segmental slide 53 to be shifted to the fullest extent for the purpose of withdrawing the web holder projecting cams 42 and 43, simultaneously, to inactivity. For the purpose of slowly rotating the needle cylinder 1 of the machine after the completion of the knitted web in order that certain functions essential to proper stitch transfer may be automatically effected, I provide the following mechanism designed to become operative immediately upon the shifting of the belt from the tight to the loose pulley 29 of the machine. As shown to best advantage in Fig. III, to the driving shaft 27 of the machine directly adjacent the loose pulley 29, is secured a ratchet wheel 75 whose teeth are, at proper times as hereinafter noted, engaged alternately by pawls 76 and 77. The first of these pawls 76 is pivoted to the upper end of an arm 78 adapted to oscillate about a fixed fulcrum 79 afforded by the frame 3 of the machine. Attached to the arm 78 is a shoe 80 which rides in an eccentric groove 81 in the outer face of the loose pulley 29 so that when the belt is applied to the latter, constant vibrating movement is imparted to said arm. Normally the pawls 76, 77 are held in the retracted or inactive position, shown in Fig. III of the drawings, by means of a guard 82 operative at one end to engage a pin 83 projecting from the pawl 76, and provided at the other with a lug 84 for engaging the pawl 77. The guard 82 is preferably formed as an integral part of a shiftable lever 85 pivoted upon the fulcrum 79 of the arm 78 aforementioned. This lever 85 engages a pin 86

on one extremity of a link 87 which is secured to a rock shaft 88 journalled in a bearing in the outer end of a fixed bracket arm 89, and it is acted upon by a spring 90 tending to depress it. Secured to the rock shaft 88 is a downwardly-curved finger 91, which, through the action of the spring 90, is caused to bear upon the periphery of a disk 92 secured to the near end of the pattern drum 17 as viewed in Fig. III, said disk having cam lugs 93 and 94 which act upon the finger 91 to rock the shaft 88 and the attached lever 85, thereby swinging the upper end of said lever 85 outwardly and thus withdrawing the guard 82 to permit the pawls 76, 77 to drop into engagement with the teeth of the ratchet wheel 75. The ratchet wheel 75, thereby, serves to drive the shaft 27 and the needle cylinder 1, step by step, the movement thus imparted to said cylinder 1 being comparatively slow so that it can be stopped without danger of being carried beyond a desired position by momentum.

As an auxiliary to the pawl 21 hereinbefore described as being operative upon the ratchet wheel 20 of the main cam drum 17, I employ a pawl 95 adapted, at a certain predetermined time to be hereinafter specified, to engage special teeth 96, 96^a, of said ratchet wheel so that said cam drum 17 can be shifted while the pawl 21 is moving rearward on its idle stroke. The pawl 95 is pivoted to one arm of a swinging element 97 mounted for free movement upon the shaft 23 of auxiliary cam drum 16 at the outer side of the frame 3 of the machine. The element 97 has a lateral extension 98, which terminates in an arcuate prolongation 99 in turn pivotally connected to the oscillating member 22 so as to derive motion therefrom. A fixed guard 100 bolted or otherwise secured to a convenient part of the frame 3 of the machine serves to confine activity of the pawl 95 to the special teeth 96, 96^a when the latter have been advanced into the province of the pawl through ordinary picking of the cam drum 17 by the pawl 21.

After the knitting of the stocking is completed, it is important in order that transfer may be effected without danger of stitch dropping, that the knitting thread be carried about the last needle fed, to a point within the circle of needles to prevent the loose end, resulting from severance of the yarn, from being caught by the hooks of the succeeding needles and there detained while the quill ring is being removed from the machine. I have accordingly devised a novel form of thread feed together with appropriate actuating mechanism which will be best understood by reference to Figs. I to III and XII to XVI inclusive of the drawings. To a hanger 105 (Fig. III) on the frame 3 of the machine is

fulcrumed a bell crank lever 106 one arm of which carries a shoe 107 adapted to the cam groove 81 in the outer face of the pulley 29 so as to impart vibratory movement to said lever. The lever 106 is connected by a link 108 to an arm 109 on a rock shaft 110 mounted in bearings on the frame 3 of the machine, and which has at its opposite extremity, an arm 111 (Figs. I to III) whereto is pivotally connected an upright bar 112, the latter having therefore a constant vertical reciprocating movement imparted thereto during the time the belt is upon the loose pulley 29. The bar 112 has, at its upper end, a laterally projecting pin 113 which normally lies beyond a lever 114 fulcrumed for free rocking movement on the yarn guide ring 14 of the machine. The reciprocating bar 112 is normally held in the position shown in Fig. I by a bifurcated engaging lug 115 on a guide arm 116, mounted so as to be free to swing on the rock shaft 110. The tail 117 of the guide arm 116 is formed with a laterally projecting finger 118 adapted to bear upon the periphery of the auxiliary cam drum 16 as shown in Fig. I. This finger 118 is in line with a recess 119 in the drum periphery (see Fig. II) so that the tail 117 of the arm 116 is permitted to move at intervals in the direction of the arrow in Fig. I to release the bar 112 from control of the guide lug 115 and permit a coiled spring 120 to swing the upper end of the bar 112 inwardly so as to bring the lateral pin 113 into the range of the lever 114 and thereby depress said lever against the action of a leaf spring 121, (Fig. XV). The lever 114 carries a stud 122 on which is pivotally mounted a yarn feed lever 123 with a guide eye 124 in its free end. The normal position of the eye end 124 of the feed 123 is in front of the needles N, as shown in Fig. XIV, the lower end of the feed 123 then resting firmly upon a supporting plate 125 on the feed ring 14, a spring 123^a serving to retain it in this position. When, however, the lever 114 is depressed by the bar 112, the yarn feed lever 123 is thrust through the needles N and carries the yarn to the inside of the needle circle, as shown in Fig. XV and in dotted lines in Fig. XVI where it is free from liability of being caught in the hooks of the needles succeeding the last one fed. Such cutting in between certain predetermined needles N, n is facilitated by virtue of the sharp taper of the guide eye 124, seen to the best advantage in Fig. XVI, and occurs at a time when the needle cylinder 1 is stationary as hereinafter noted.

Pivotedly mounted at 126 upon the yarn guide ring 14 is a bell crank lever 127 which has, on one side, a projecting lug 128 adapted, when the lever 114 is depressed, to be struck by a projecting pin 129 on said lever, the lever 127 being then swung in the direc-

tion of the arrow in Fig. XII against the tension of a spring 130, until the pin 129 has cleared the lug 128 and passed from the upper to the under surface of the same, as shown in Fig. XIII. The lug 128 then prevents return of the lever 114 and yarn feed 123 from the position shown in Fig. XV to that shown in Fig. XIV until the lever 127 is carried away from a stop pin 131 projecting from an adjustable plate 132 when the ring 14 is swung upward in order to carry the yarn feed 123 away from the needles when it is desired to apply the transfer ring to the latter. As soon, therefore as the bell 15 crank lever 127 clears the pin 131, the yarn feed 123 returns automatically to the normal position of Fig. XIV relative to the ring 14, under the combined action of the springs 121 and 123^a so as to be ready for action 20 when the ring 14 is lowered.

The operation of the machine is as follows:

After the machine has completed the stocking which it is designed to produce, the drive belt is automatically shifted from the tight 25 to the loose pulley 29. This is effected under control of the main cam drum 17 through interposed mechanism such as customarily provided in stocking knitters for this purpose, and which is operative in a well known manner. The machine proper comes to rest as the pawl 21 completes a last retractive movement relative to the ratchet wheel 20 without having any effect upon the latter. 30 However, while this idle retractive movement of the pawl 21 takes place, the auxiliary pawl 95 is being advanced to engage the first special high tooth 96 of the main cam drum 17, the latter having been progressed incidental to the normal operation 35 of the machine to bring said special high tooth 96 into engaging position. As a result of this action, the main cam drum 17 is advanced over that portion thereof ordinarily 40 allowed for the measuring of a certain number of looper's rounds (which are, in the present instance, dispensed with), when the thrust bar 9 is raised to withdraw the knitting cam block 6 in a manner already explained. 45 At the same time, the curved finger 91 is engaged by the first lug 93 of the disk 92 (Fig. III) with the result that the lever 85 is thrust aside carrying with it the guard 82 and thus permitting the pawls 76 and 77 50 to become active upon the ratchet wheel 75.

While the conditions thus far recited prevail, the position of the auxiliary cam drum 16, the latter having been progressed simultaneously with the main cam drum 17 by virtue of the interposed gear train 18, 19 will be as follows with regard to the instrumentalities which it controls:

The lower end 118 of the tail 117 of the guide arm 116 resting within the recess 119 and the vertically reciprocating rod 112 be-

ing in position for engaging its pin 113 with the lever 114, Figs. I, II and III; the internal cam lug 33 engaging the roller 38 at the lower end of pull rod 34, the elevating or stitch cam 30 in the raised position shown in dotted lines in Fig. I; and the cam lug 71 engaging the thrust rod 70 and maintaining the swinging plate 47 pressed forward, as shown in Fig. VI, with the sinker 75 projecting cam 43 in readiness to urge the sinkers or web holders 40 abnormally inward relative to the needles N.

As a consequence of these conditions, the first action to take place is the projection of the yarn feed 123 through the needles N to the position illustrated in Fig. XV as the rod 112 makes its initial descent. The timing of this mechanism is so ordered that the projection of the yarn feed 123 is accomplished in a substantially instantaneous manner and at the instant of dwell of the needle cylinder 1 consequent upon the first pick of the ratchet wheel 75. The thread is thus brought to the inside of the needle circle around the last needle fed so that the loose end resulting from severance, for which the usual instrumentalities ordinarily provided for the purpose may be employed, cannot possibly be caught by the hooks of succeeding needles, nor be subsequently jammed between the transfer quills q by the web holders 40.

Continued stepwise rotation of the needle cylinder 1 under propulsion of the ratchet wheel 75 results in the elevation of all the stitch needles by the depressing cam 30, while the cam 31 cooperates to concurrently depress the long butt needles "N" of the series for the purpose of demarcation as previously noted. Also contemporaneously with the stepping about of the needle cylinder 1, the sinker wales "w" of the last course of stitches "s" held by the needles are urged back upon the web as shown in the diagrammatic illustration of Fig. XI thereby affording enlarged spaces immediately behind the short butt needles "n" for better reception of the quills "q" of the transfer ring 32. As a consequence of the rotation of the main drive shaft 27, the pawl 21 is maintained in activity so that upon a complete revolution of the needle cylinder 1, the main cam drum 17 has been advanced with the cam lug 93 positioned beyond the curved finger 91 to prevent further picking of the ratchet wheel 75 by the pawls 76, 77 due to restoration of the pawl guard 82 to its normal or active position. Thereupon the machine comes to absolute rest except for idle oscillation of the parts directly subject to the eccentric groove 81 of the loose pulley 29.

This cessation of action affords an opportunity for the operative to swing the yarn guide ring 14 out of the way for the purpose

of placing a split transfer ring, such as previously referred to herein, upon the needles of the machine under guidance afforded by the demarcation in the levels of the tops of the complementary long and short butt groups N , n , respectively, of said needles.

After the placing of the transfer ring 32, as shown in Fig. VII, the machine is started by manual shifting of the driving belt to the tight pulley resulting in the release of the thrust bar 9 to permit automatic restoration of the knitting cams 7—Fig. VIII—to activity under the action of the spring 12, the movement of the main cam drum 17 being accompanied by corresponding progression of the auxiliary cam drum 16 resulting in the nullification of the various previously described settings of the instrumentalities controlled by the latter drum.

A turn or two of the needle cylinder 1 with the knitting cams 7—7 active suffices for the needles N , n to cast their stitches, when further advancement of the main cam drum 17 results in a second automatic shifting of the belt to the loose pulley 29. During such shifting, the auxiliary pawl 95 engages the second high tooth 96^a on the main cam drum 17 as a result of which the latter is shifted to cause the thrust bar 9 to again withdraw the knitting cams 7—7, these events occurring in precisely the same manner as in the previous instance. Likewise, the mutual progression of the auxiliary cam drum 16 results in the engagement of the cam 67 with the roller 66 of thrust rod 65 releasing the catch 60 through the shifting of the inclined spring tongue 61 of link 62 so that the segmental plate 53 (Fig. IV) is shifted to the position shown in Fig. V when the lug 72 encounters the thrust rod 70. The shifting of the segmental plate 53 as just noted is accompanied by simultaneous retraction of the web holder projecting cams 42, 43. Thus in the course of subsequent stepwise rotation of the needle cylinder 1 under progression of the ratchet wheel 75, the web holder's 40 are withdrawn relative to the needles while said needles are leveled in the usual way as a result of the retraction of the knitting cams 7—7. After the completion of a rotation or two, the curved finger 91 (Fig. III) drops off the cam lug 94 with cessation of all functional activity of the machine, when the transfer ring 32 may, with the stitches of the terminal courses of the knitted web impaled upon its points or quills q , be removed from the machine.

From the foregoing it will be obvious that transfer is, in accordance with my invention, effected in a substantially automatic manner, except perhaps for the placing and removing of the transfer ring 32 and an incidental manual shifting of the drive belt, and that the operation can be effected

without requiring any special skill on the part of the operative.

Having thus described my invention, I claim:

1. The combination in a knitting machine, of means for bringing the needles to latch clearing position and at the same time of leveling them with certain needles slightly beyond others for purpose of demarcation to facilitate application of a transfer device, in definite relation, to the needles. 70

2. The combination in a knitting machine, of means for leveling the needles with certain needles slightly beyond others for the purpose of demarcation to facilitate application of a transfer device, in definite relation, to the needles. 75

3. The combination in a knitting machine, of a pair of associated cams, adapted for operation upon the withdrawal of the knitting cams, one effective upon all the needles to move them to a predetermined position, and the other only upon certain of the needles for retracting them slightly with respect to the others for the purpose of demarcation in leveling to facilitate application of a transfer device, in definite relation to the needles. 80

4. The combination in a knitting machine having long and short butt needles, of a cam operative upon all the needles to move them to a predetermined position, and an associated cam operative only on the long butt needles of the series to retract them slightly for the purposes of distinction in the level of the two groups to facilitate application of a transfer device in definite relation to the needles. 85

5. In a knitting machine with transfer mechanism, the combination of a yarn feed, a needle cylinder, a cam ring, means for imparting slow relative rotation to the cylinder and the cam ring in connection with a transfer operation with dwell periods in such rotation, a cam drum controlling said transfer mechanism, means for normally progressing the cam drum, and auxiliary means cooperative with said cam drum to effect substantially instantaneous withdrawal of the yarn feed from activity at said dwell periods. 90

6. In a knitting machine with transfer mechanism, the combination of a yarn feed, a needle cylinder, a cam ring, means for imparting slow relative rotation to the cylinder and the cam ring in connection with a transfer operation with dwell periods in such rotation, a cam having special high teeth for controlling said mechanism, a main pawl for normally progressing the cam drum, and an auxiliary pawl cooperative with the special high teeth during certain retractive strokes of the main pawl to effect substantially instantaneous withdrawal of the yarn feed from activity at said dwell periods in preparation for transfer. 95

7. In a knitting machine with transfer mechanism and a yarn feed, the combination of a cam drum with a portion of its surface devoted to control the knitting instrumentalities of the machine during the transfer period, a main pawl for effecting normal progression of the drum and an auxiliary pawl cooperative with special high teeth on the cam drum to progress the aforesaid portion of the latter and effect substantially instantaneous withdrawal of the yarn feed from activity in preparation for transfer. 10
8. In a knitting machine with transfer mechanism, the combination of a yarn feed, a needle cylinder, a cam ring, means for imparting slow relative rotation to the cylinder and the cam ring in connection with a transfer operation with dwell periods in such rotation, a cam drum with a portion of its surface devoted to control the knitting instrumentalities of the machine during the transfer period, a main pawl for normally progressing the drum, and an auxiliary pawl adapted to progress the aforesaid portion of the cam drum during idle retractive movements of the main pawl whereby substantially instantaneous withdrawal of the yarn feed from activity at said dwell periods is effected in preparation for transfer. 20
- 25 9. In a knitting machine the combination of a main drive mechanism for rotating the drive shaft during the knitting periods, and an auxiliary drive mechanism for driving the shaft during a period of web transfer including a ratchet wheel secured to said shaft, and means coordinated with the loose pulley of the machine for progressing the ratchet. 30
- 35 10. In a knitting machine the combination of a main drive mechanism for rotating the drive shaft during the knitting periods, and an auxiliary drive mechanism for driving the shaft during a period of web transfer including a ratchet wheel secured to said shaft, a pawl, a swinging arm carrying the pawl, and an eccentric on the loose pulley of the machine for oscillating said arm. 40
- 45 11. In a knitting machine the combination of a main drive mechanism for rotating the drive shaft during the knitting periods, and an auxiliary drive mechanism for driving the shaft during a period of web transfer including a ratchet wheel secured to said shaft, pawling means coordinated with the loose pulley of the machine for progressing the ratchet, and means governed by the pattern drum for controlling the active periods of the pawling means. 50
- 55 12. In a knitting machine, the combination of needles, web holders, web holder projecting cam, and means for shifting said cam in inducing an abnormal thrust of the web holders to enlarge the stitches of the terminal course of the knitted web and thereby facilitate subsequent introduction of the 60 quills of a transfer device thereinto. 65
13. In a knitting machine, the combination of needles, web holders, a web holder projecting cam, means operative for shifting said cam in inducing an abnormal thrust of the web holders to enlarge the stitches of the terminal course of the knitted web and thereby facilitate introduction of the quills of a transfer device thereinto, and means for subsequently retracting said cam to release the web to the transfer device. 70 75
14. In a knitting machine, the combination of needles, web holders, a web holder projecting cam functional to impart an abnormal thrust thereto, and means whereby said projecting cam may be retracted permitting recession of the web holders for the purpose of releasing the web for transfer. 80
15. A knitting machine with means facilitating the transfer of a knitted web from the needles thereof to the quills of a transfer device, including in combination, needles, web holder projecting cams, a slide controlling one of said cams, a swinging plate carried by the slide and controlling the other of said cams, and means whereby movement may be selectively imparted to said slide and plate. 85 90
16. A knitting machine with means facilitating transfer of a knitted web from the needles thereof to the quills of a transfer device, including in combination, web holders, web holder projecting cams, a slide controlling one of said cams, a lock normally holding the slide against movement, a swinging plate carried by the slide and controlling the other of said cams, a thrust bar adapted to impart movement to the swinging plate, and also to the sliding plate when released by the lock. 95 100
17. A knitting machine with means facilitating transfer of a knitted web from the needles thereof to the quills of a transfer device, including in combination, web holders, web holder projecting cams, a slide controlling one of said cams, a lock normally holding the slide against movement, a swinging plate carried by the slide and controlling the other of said cams, a thrust bar adapted to impart movement to the swinging plate and a second bar for actuating the lock to release the slide to the first mentioned bar for simultaneous movement with the swinging plate. 105 110 115
18. The combination in a knitting machine, of knitting needles, and a yarn feed capable of being abnormally thrust radially through the needles to insure positioning of the loose end of the yarn remaining after severance to the back of the needles, thereby to prevent the same from being caught by the needle hooks and stripping the stitches from the quills of a transfer device during removal of the fabric from the machine. 120 125
19. The combination in a knitting ma- 130

chine, of a needle cylinder, a yarn feed, means for intermittently rotating the needle cylinder after completion of the knitting to prepare the knitting instrumentalities for transfer of the knitted web, and means for abnormally thrusting the feed radially through the needles during a quiescent period of the needle cylinder to prevent further feeding of the yarn.

20. In a knitting machine the combination of needles, a yarn feed shiftable to inactive position to draw the loose end of the yarn remaining after severance back of the needles to prevent its being caught by the needle hooks and stripping the stitches from the quills of a transfer device during removal of the fabric from the machine, and instrumentalities for actuating the feed as aforesaid including a lever, a reciprocating member, and time-controlled means for moving the reciprocating member into the province of the lever to shift the feed at the completion of a knitting operation.

21. In a knitting machine the combination of a main drive mechanism for rotating the drive shaft during the knitting periods, and an auxiliary mechanism for driving the shaft during the period of web transfer actuated by the loose pulley of the machine.

22. In a knitting machine the combination of a main drive mechanism for rotating the drive shaft during the knitting periods, an auxiliary drive mechanism for driving the shaft during the period of web transfer comprising a ratchet wheel operatively connected with said shaft, and means coordinated with the loose pulley of the machine for progressing the ratchet wheel.

23. In a knitting machine the combination of a main drive mechanism for rotating the drive shaft during the knitting periods, an auxiliary drive mechanism for driving the shaft during the period of web transfer comprising a ratchet wheel operatively connected to said shaft, and a pawl with oscillating means actuated from the loose pulley of the machine for activating said ratchet wheel.

24. In a knitting machine the combination of a main drive mechanism for rotating the drive shaft during the knitting periods, an auxiliary drive mechanism for driving the shaft during the period of web transfer actuated by the loose pulley of the machine, and means governed by the pattern drum for connecting said auxiliary drive mechanism to said shaft.

25. In a knitting machine the combination of a main drive mechanism for rotating the drive shaft during the knitting periods, an auxiliary drive mechanism for driving the shaft during the period of web transfer and including a ratchet wheel operatively connected to said shaft, means coordinated with the loose pulley of the machine for progress-

ing the ratchet wheel, and means governed by the pattern drum for controlling the operative periods of the means co-ordinated with the loose pulley.

In testimony whereof, I have hereunto signed my name at Philadelphia, Pennsylvania, this 14th day of February, 1923.

LOUIS N. D. WILLIAMS.
